UNITED STATES PATENT OFFICE.

SAMUEL S. MATTHES, OF MANSFIELD, OHIO, ASSIGNOR TO THE OHIO BRASS COMPANY, OF MANSFIELD, OHIO, A CORPORATION OF NEW JERSEY.

REELING DEVICE.

1,866,198.

Specification of Letters Patent. Patented Jan. 18, 1921.

Application filed April 9, 1919. Serial No. 288,783.

To all whom it may concern:

Be it known that I, SAMUEL S. MATTHES, citizen of the United States of America, residing at Mansfield, in the county of Rich- 5 land and State of Ohio, have invented cer- tain new and useful Improvements in Reeling Devices, of which the following is a specification.

This invention relates to improvements in 10 reeling devices, and I have described its use and operation as applied to trolley retrievers although its use is not limited to trolley retrievers.

One object of the invention is to provide a 15 device of this character which may be adjusted to obtain any desired amount of retrieving action within the limits of the device.

Another object is to provide a reeling de- 20 vice embodying mechanism whereby the set- ting of the retrieving mechanism is controlled by the tension of the retrieving spring.

A further object is to provide a device of 25 the character referred to which will be simple, durable, reliable and compact in construction and effective and efficient in operation.

To the attainment of these ends and the 30 accomplishment of other new and useful ob- jects as will appear, the invention consists in the novel features of the construction, combination and arrangement of the several parts to be hereinafter described more fully, and claimed, and shown in the accompan- 35 ing drawings, in which:

Figure 1 is a side view of a reeling mech- 40 anism embodying the principle of my in- vention and shown partly in section to illus- trate the constructional arrangement of the various parts.

Fig. 2 is a sectional view taken on the lines 2-2 of Fig. 1.

Fig. 3 is a detail sectional view taken on the line 3-3 of Fig. 2.

Fig. 4 is a sectional view substantially on the line 4-4 of Fig. 1, and showing the mechanism set up or the retrieving disk in interlocked relation with the case.

Fig. 5 is a detail view of the retrieving 50 disk.

Fig. 6 is a perspective view of the pawl.

Fig. 7 is a view similar to Fig. 5, indicating the centrifugal dog in the act of releasing or unlocking the retracting mechanism 55 (dotted lines) and also showing said mech-

anism unlocked and about to commence its retracting action on the pole, (full lines).

Fig. 8 is a sectional view substantially on the line 8-8 of Fig. 1, showing the parts in interlocked relation and in which position 60 the retrieving spring is wound up, or set.

Fig. 9 is a similar view as Fig. 8, showing the locking device out of engagement with the retrieving disk and also showing the means whereby the device is maintained in 65 disengaged condition.

Fig. 10 is a similar view as Figs. 8-9 showing the resetting mechanism in position preparatory to interlocking the parts.

My invention as applied to trolley re- 70 trieviers consists in providing a locking de- vice which normally operates to hold the power spring under tension and which shall automatically be released to permit unwinding of the power spring to wind up the trolley 75 rope. It further consists in providing means whereby the locking device is held in released position during the unwinding of the power spring and which tends to maintain the locking device in inoperative posi- 80 tion during unwinding of the rope, thereby to effect the setting or winding up of the power spring. Furthermore, it consists in providing means which operate to permit movement of the locking device into opera- 85 tive position when the power spring has been set or wound up to a predetermined tension. It consists further in providing means whereby the first mentioned means may be adjusted to obtain any desired amount of tension 90 on the power spring prior to the reengagement of the locking device.

The same reference characters indicate the same parts throughout the various views.

In carrying out the preferred form of my 95 invention I provide a casing 1 having a cover 2 removably secured thereto in any suitable manner. Mounted within a recess formed in the casing is a power or retrieving spring 3, which has its outer end secured to the 100 casing and its inner end connected, in any suitable or well known manner, to the hub 4, of a driver 5, which is rotatably mounted on the shaft 6, secured within the casing. The driver 5 comprises a driving arm 7, which 105 extends and has a limited amount of movement between stops 8 and 9, provided on one side of the retrieving disk or retrieving member 10, which is rotatably mounted on the shaft 6 and normally interlocked with 110

the casing against relative rotation by means of the locking device or pawl 11, which is pivotally secured to the casing at 12, and has its free end formed for engagement 5 with the shoulder 13, thereby to prevent rotation of the disk by the action of the power spring as shown in Figs. 4 and 8. A movable member 14 is pivotally secured at 15 to the driving arm 7 of the driver and has one 10 end of a tension spring 16 connected thereto, while the other end of the spring is connected to the driving arm 7. This spring tends to constantly urge the member 14 to rotate toward and into engagement with 15 its coöperating stop lug 17, the purpose of which will hereinafter be described.

When the retrieving member 10 is in normally interlocked engagement with the casing, as above stated, the retrieving spring 20 3 is fully wound up or set, the driving arm 7 held in engagement with the stop 8 by the tension on the retrieving spring, and the movable member 14 held in spaced relation with its stop 17 against the action of the 25 spring 16 by engagement with the locking device or pawl as indicated at 18.

The retrieving disk 10 is provided with a lug 20, through which extends a screw 21, having threaded engagement with one end 30 of a tension spring 22, the other end of which is connected to the driving arm 7 of the driver. This spring tends to rotate the arm 7 against the action of the retrieving spring, and is adapted to move the arm 35 9 when the tension on the retrieving spring weakens by reason of its unwinding when brought into action. This spring, which will be referred to hereinafter as the "con- 40 trol" spring, has its one end secured to the disk by means of the screw 21, as before stated, and it will be apparent that by this arrangement the spring may be adjusted to obtain any required or desired amount 45 of tension.

Rotatably mounted, preferably upon the hub 23 of the retrieving disk, is a drum 24, adapted to receive the trolley rope 25. The drum is formed with a recess 26 to receive 50 the service spring 27 which normally operates to keep the trolley rope taut. The outer end of this spring is secured to the drum, while the inner end thereof may be connected in the usual manner, to a sleeve 28, ad- 55 justably mounted by means of ratchet teeth, not shown, or otherwise. By adjustment of the sleeve 28, the tension on the service spring may be increased or decreased to suit various conditions.

60 In order to throw the locking pawl 11 to release the retrieving disk and to interlock said disk with the drum, the latter carries a plurality of centrifugal dogs 30, which are pivotally mounted in suitable sockets or 65 bearings 31 formed in integral bosses 32 on

the side of the drum adjacent the retrieving member 10. When normally operating these dogs are yieldably maintained in inward or retracted position by springs 33, the free ends of the dogs resting against the adjacent bosses, as clearly shown in Figs. 4 70 and 7. These dogs are arranged so that they will be sensitive to abnormal fluctuations of the trolley pole, such for instance as when the trolley pole leaves the trolley wire and flies upwardly. Because of the undue speed of the drum incident to the quick upward movement of the trolley pole the dogs will move outwardly against the peripheral flange 34 on the retrieving disk under the 75 action of centrifugal force.

It will be noticed that the locking pawl 11 has a flange 35 which when the pawl is in locking position extends within the flange 34 and hence within the path of the free 80 ends of the centrifugal dogs. In conse- 85 quence, the dog which at the instant is nearest to the pawl will strike the flange and force it outwardly, thus moving the pawl out of locking engagement with the retrieving 90 disk. In order to insure positive releas- 95 ing action on the part of the dogs, I pro- 100 vide an outstanding rib 36 on the face of the retrieving disk. This rib is located adjacent the locking pawl to provide a comparatively 105 narrow space between the rib and the flange 34. In addition the free ends of the dogs are provided with extensions or shoes 37 of sufficient thickness to pass through the space 110 between the rib 36 and the flange 34. Con- 115sequently, the free end of the particular dog in action will positively force the pawl out- 120wardly and out of interlocked engagement with the retriever disk. Fig. 7 shows in dotted lines one of the dogs in the act of entering said space and tripping or throw- 125 ing outwardly the latch. Assuming now that the pawl has been thrown out and the retrieving disk released as indicated in Fig. 7, it now remains to lock the disk and the drum together so that said disk will actuate 130 the drum in a direction to wind up the rope and pull down the trolley. This is accom- 135plished by the centrifugal dog, which after tripping the pawl continues its movement toward and into engagement with the shoulder 38, formed in the periphery of the flange and thereby positively interlocks the disk with the drum and the drum will then be rotated with the retrieving disk and wind up 140 the trolley rope.

When the locking pawl 11 moves out of engagement with the retrieving disk it also releases the movable member 14 which im- 145 mediately moves by the action of the spring 16 into engagement with its coöperating stop lug 17, (see Fig. 9), where it operates to prevent reengagement of the pawl 11 prior to the unwinding of the power spring 150 and tends to maintain said pawl in disen- 155

gaged position until the power spring is again set or wound up to the proper or desired tension. During this movement of the member 14 it is brought into frictional engagement with and slightly depresses a leaf spring 39 (see Fig. 3 for details) which operates to retard movement of the member 14. The spring 16 is assisted in overcoming the retarding action of the spring 39 by the momentum of the part 14, as it is not sufficiently strong to overcome alone this retarding action as will be brought out later.

The operation of my invention is as follows: When the power spring is fully wound up or set and the parts are in their normal position they will be as represented in Figs. 2, 4 and 8. The locking pawl 11 will be in engagement with the retrieving disk 10 holding the movable part 14 in inoperative position away from its coöperating stop 17. The driving arm 7 of the driver will be held in engagement with the stop 8 against the action of the control spring 22 by the tension of the power spring and the centrifugal dogs 30 held in engagement with the bosses 32 as shown. In this condition the drum will be under the action of the service spring 27 and the trolley rope may be wound up or unwound thereon. When the rope is rapidly unwound from the drum as when the trolley pole jumps the wire, the sudden impulse or rapid rotation of the drum will cause the dogs 30 to move outwardly by centrifugal force and move the locking pawls out of engagement with the retrieving disk and interlock the drum with the retrieving disk in the manner hereinbefore described. When this has taken place the parts will be in the position shown in Figs. 7 and 9 (full lines). Next the retriever disk and the drum will be caused to rotate in the rope winding direction by the power spring 3 through the medium of the driver 5 and the control spring 22. As the drum rotates, the power spring, which is normally held under tension slightly higher than that of the control spring 22, weakens, thereby permitting the control spring to act upon the driver 5 and move the driving arm 7 into engagement with the stop 9. This positioning of the driving arm 7 shifts the pivot point 15 of the movable part 14 which by reason of its free end having engagement with stop lug 17, is thereby caused to change its position on the arm. Fig. 9 indicates in dotted lines the relation of the parts when the arm is in engagement with the stop 9, and in which condition of the parts the power spring is unwound and the trolley rope wound up. The interlocked disk 10 and drum 24 are free to rotate in a rope-winding direction under action of the spring 3 and without interference by the dog 11 for the reason that the movable part 14 has moved into the position shown in Fig. 9 and

closed the space in the slot B in the disk 10, thereby preventing the dog 11 from re-engaging the disk at the end of one revolution and preventing further rotation of the disk and drum in a rope-winding direction. 70

To set or restore the parts to their normal operating condition after the device has operated as above, it is only necessary to pull out on the trolley rope, thereby unwinding the same and turning the drum and the retriever disk in the direction indicated by arrow in Figs. 8 and 10. As the rope is pulled out and the disk revolves, the driving arm 7 of the driver is held in engagement with the stop 9 by the control spring 22, which is exerting a greater tension at first than the spring 3, the locking pawl 11 is prevented from entering the slot B in the disk by the movable part 14, and the power spring 3 will be wound up until its tension 80 becomes equal to or balances the tension of the control spring 22. Then upon continued rotation of the parts in the same direction and the consequent further tensioning of the power spring 3, the control spring will be 85 caused to yield and the driving arm 7 of the driver move toward and into engagement with the stop 8 under the influence of the power spring. By this positioning of the driving arm 7 the movable part 14 will be 90 carried out of engagement with the stop 17, thereby opening a portion of the slot B as indicated at D; (see dotted line position of parts Fig. 10). In order to yieldably maintain the part 14 in this position on the arm, 100 I make use of the flat or leaf spring 39, (see Fig. 3 for details), already referred to and which engages and thereby resists movement of said part relatively to the pawl 11. With this construction, continued rotation 105 of the disk brings the opening D in alignment with the lip 40 of the locking pawl which will then move into said opening, as shown in Fig. 10. In consequence of this relation of the parts the lip 40 of the pawl 110 is positioned in the path of the movable part 14, and said lip will in the continued rotation of the disk shift the part 14 to completely open the slot B and thereby permit movement of the pawl into the opening 115 where it is in locking position. When the pawl is in this position further rotation of the disk to wind up the power spring is prevented by the shoulder 41 of the disk which is adapted to limit said rotation by 120 engagement with the shoulder 42 of the pawl, and rotation of the disk in the opposite direction, or to unwind the spring, is prevented by engagement of the end 43 of the pawl with the shoulder 13 of the disk. 125 Thus it will be obvious that when the pawl is in locking position it positively prevents rotation of the disk in either direction. Figs. 2, 4 and 8 indicate the disk and pawl in normal interlocked position. 130

It now remains to release the drum from the retriever disk, which it will be remembered were held interlocked while the parts were being restored to normal operative condition, and as shown in Fig. 7. This is accomplished as soon as the pull on the trolley rope is relaxed, whereupon the drum will start to rotate in the opposite direction under the influence of the service spring 27, and in this movement it carries the centrifugal dog 30 out of engagement with the stop shoulder 38 of the disk. This dog moves out until it passes the end of the guide rib 44 and it is then drawn inwardly against the boss 32 by its spring 33, thus finally unlocking the drum from the disk and leaving the drum free to again normally wind up and unwind the trolley rope.

It will be noted from the foregoing that the mechanism which automatically governs the restoration of the device to the normal operating condition is controlled by the spring 22, and that by varying the tension of this spring as herein provided, the parts may be adjusted to obtain any desired tension on the power spring when in wound up or set position within the limits of the construction.

It will be obvious to one skilled in the art, after having obtained an understanding of my invention from the disclosures herein made, that my invention may be modified without departing from the scope and spirit of the invention, and I wish my invention to be understood accordingly.

I claim as my invention:

1. A reeling device comprising a casing, a power spring therein, means for winding up the spring, and mechanism normally interlocked and coacting with the casing for holding the spring under tension, said mechanism comprising means controlled and actuated by the tension in the spring for compelling the winding up of the spring to a predetermined tension before the interlocking of the mechanism with the casing can be accomplished.

2. A reeling device comprising a casing, a power spring therein, means for winding up the spring, and mechanism normally interlocked and coacting with the casing for holding the spring under tension, said mechanism comprising means actuated by the tension in the spring for preventing the winding up of the spring to exceed a predetermined tension before the interlocking of the mechanism with the casing is accomplished.

3. A reeling device comprising a casing, a power spring therein, means for winding up the spring, mechanism in operative engagement with the casing for normally holding the spring under tension, said mechanism comprising means actuated by a predetermined tension in the spring for con-

trolling the mechanism, and adjustable means for varying said tension.

4. A reeling device comprising a casing, a reel mounted therein adapted to receive and wind up a trolley rope, a power spring to rotate the reel, means whereby the spring is wound up by rotation of the reel in a rope unwinding direction, means operating to normally hold the spring under tension when fully wound up, and means controlled by the tension on the spring and co-acting with said holding means to limit the winding up tension of the spring.

5. A reeling device comprising a casing, a rotatable reel therein adapted to receive and wind up a trolley rope, a power spring to rotate the reel in the rope winding direction, means whereby the spring is wound up by rotating the reel in the rope unwinding direction, a locking device coacting with the casing for holding the spring under tension, and means actuated and controlled by the tension on the power spring and co-operating with the locking device to render the latter ineffective prior to the winding up of the spring to a predetermined tension.

6. A reeling device comprising a casing, a rotatable reel therein adapted to wind up a trolley rope, a power spring to rotate the reel in the rope winding direction, mechanism to wind up the spring by rotation of the reel in the opposite direction, a holding device coacting with the casing for maintaining the spring under tension when wound up, and means controlled by the tension on the spring for maintaining the holding device in inoperative position until the power spring is wound up to a predetermined tension.

7. A reeling device comprising a casing, a shaft therein, a reel mounted on the shaft adapted to receive and wind up a trolley rope, a power spring to rotate the reel in the rope winding direction secured at one end to the casing, mechanism whereby the spring is wound up by rotation of the reel in the rope unwinding direction engaging the other end of the spring, a locking device normally coacting with the casing for holding the spring under tension, and means associated with said mechanism and controlled by the tension of the power spring to cooperate with said locking device for maintaining the locking device inactive during rotation of the reel to wind up the rope.

8. In a reeling device adapted to have a rope wound upon and unwound therefrom, the combination of a retrieving member, a power spring tending to rotate the member in one direction, means for rotating the member in the other direction and against the action of the spring to wind up the spring, a device for locking the member

105

115

120

130

against rotation in the direction urged by the spring, means for actuating said locking device to release the member, and mechanism comprising a pair of coöperating 5 members for maintaining the locking device in released position during rotation of the retrieving member in a spring unwinding direction, said pair of members controlled by the tension of the spring and operating to permit the locking device to return to its locking position after the spring 10 has been wound up to a predetermined tension.

9. An article of manufacture comprising 15 in combination a retrieving member, a power spring for actuating the member and mechanism connecting the spring and member whereby the power of the spring is transmitted to the member, said mechanism comprising 20 an element having a rotative movement relatively to the member and controlled by the spring when wound up to a predetermined tension.

10. An article of manufacture comprising 25 in combination a retrieving member, a power spring to rotate the member, and mechanism interposed between the spring and member and by means of which the member is driven by the spring, said mechanism comprising 30 an element having engagement with the spring and mounted for relative rotation with the member and being normally held in engagement with the member by the tension in said spring.

35 11. An article of manufacture comprising in combination a rotatable member, a power spring for rotating the member, and connecting mechanism interposed between the member and the spring, said mechanism 40 comprising a driving element connected to and controlled by the tension in the spring and having yieldable engagement with the member providing for movement of the mechanism relatively to the member during 45 operation of the device.

12. In a reeling device, the combination of a retrieving member, a power spring to rotate the member and mechanism interposed between the spring and the member, said 50 mechanism comprising a driving element connected to the spring and movable from one position to another relatively to the member by tension of said spring when the spring is being wound up.

55 13. In a trolley retriever, the combination of a normally stationary retrieving member, a power spring tending to rotate the member in one direction, a latch for holding the member against rotation by the spring, 60 means actuated by centrifugal force to release the latch, and connecting mechanism interposed between the spring and the member through which power of the spring is transmitted to the retrieving member, said 65 mechanism comprising a member controlled

by the latch and movable into operative position when released by relative movement of the latch for preventing movement of the latch into holding position during rotation of the retrieving member by the spring. 70

14. In a reeling device, the combination with a retrieving member, a power spring tending to rotate the member in one direction, means for rotating said member in the other direction and against the tension of 75 said spring, a latch for locking said member against rotation in the direction urged by the spring, and mechanism connecting the member and the spring and movable relatively to the member and into normal position by tension of the spring, said mechanism comprising a movable member for controlling the setting of the latch and normally held in inoperative position by engagement with the latch. 80

15. In a reeling device, the combination of a retrieving member, a power spring for rotating the member in one direction, a lock operable when set to hold the retrieving member against rotation in either direction, 90 and connecting mechanism interposed between the member and the spring for transmitting power of the spring to the member and for controlling the setting of the latch, said mechanism comprising a driving element connected to the spring and normally held in yieldable engagement with the retrieving member by tension of the spring, and a movable member carried by said element and normally controlled by the latch. 95

16. In a reeling device, the combination of a retrieving member having two shoulders spaced apart, a power spring for rotating the member in one direction, a latch operable when set to hold the retrieving member against rotation by the spring, means for actuating the latch to release the disk, and connecting mechanism interposed between the member and spring for transmitting power of the spring to the member 105 and for controlling the latch, said mechanism comprising a driving element having engagement with the power spring and arranged and constantly urged in one direction of rotation between said shoulders by tension of the power spring, a control spring tending to rotate said element in the opposite direction and against action of the power spring, said element normally maintained in engagement with one of said shoulders by tension of the power spring and rotated relatively to the retrieving member and into engagement with the other shoulder by action of the control spring during 115 unwinding of the power spring, and means actuated by the relative movement between said element and member for controlling the setting of the latch. 120

17. In a reeling mechanism the combination of a case, a retrieving member therein, 130

a spring to rotate the member, an automatically operating device normally holding the member in interlocked relation with the case against rotation by the spring, said device and member provided with coöperating faces whereby rotation of the member in either direction is limited when the member is in interlocked relation with the case, centrifugally controlled means for actuating the device to release the retrieving member and means controlled by the tension in the spring to control the reengagement of the holding device and the retrieving member.

18. In a reeling mechanism the combination of a case, a rotatable member therein, means for normally interlocking the member with the case against relative rotation, a power spring tending to rotate the member in one direction, means for rotating the member in the other direction, and mechanism connecting the spring and member, said mechanism comprising a driving element connected to the spring and arranged for relative rotation with the member and operating to transmit power of the spring to the member and having a movable part mounted thereon to engage with the interlocking means for allowing rotation of the member.

19. In a reeling mechanism the combination with a case, a retrieving member rotatable therein, a power spring normally wound up for rotating the member, means for normally interlocking the member with the case against relative rotation, and means for disengaging said interlocking means to permit rotation of the member, of mechanism interposed between the spring and the member, said mechanism comprising a driving element having engagement with the spring and a yieldable connection with the member for transmitting power of the spring to the member, and means secured to said element and rotating therewith for controlling the interlocking means.

20. In a reeling mechanism the combination with a case, a rotatable member therein, means for normally interlocking the member with the case against relative rotation, means to engage with and thereby disengage the locking means to permit rotation of the member, and a power spring normally held under tension, of mechanism connecting the spring and member for transmitting power of the spring to the member and coacting with said member to maintain the locking means in disengaged position during rotation of the member, said mechanism comprising a power element having engagement with the power spring and normally held in engagement with the member by the tension of said spring and resilient means connecting said power element and member and normally yielding to the tension of the power spring for actuating the element relatively to the member during unwinding of the spring.

21. A reeling device comprising a casing, a shaft mounted thereon, a reel rotatably mounted on the shaft to receive and wind up a trolley rope, a power spring in the casing to rotate the reel in one direction, means whereby the spring is wound up by rotation of the reel in a rope unwinding direction, means to normally hold the spring under tension when fully wound up, and means controlled by the tension on the spring and coacting with the holding means to limit the winding up of the spring to a predetermined tension, said last mentioned means comprising a driving element rotatably mounted on the shaft and connected to the spring for transmitting power of the spring to the reel and normally controlled by tension of the spring.

22. In a reeling device, the combination of a retrieving member, a power spring normally wound up and tending to rotate the member in one direction, means for rotating the member in the other direction to wind up the spring, a latch pivotally secured to the casing for locking the member against rotation in either direction, means centrifugally controlled for releasing the latch to permit rotation of the member in either direction and mechanism interposed between the member and spring and controlled by the tension of the power spring and coöperating with the latch for compelling the winding up of the spring to a predetermined tension prior to locking the member against rotation in the direction to wind up the spring.

23. In a reeling mechanism, the combination of a rotating member, a power spring normally wound up and tending to rotate the member in one direction, means for rotating the member in the other direction to wind up the spring, a latch for locking the member against rotation in either direction, means for releasing the latch and means controlled by the tension of the power spring and coöperating with the latch for compelling the winding up of the spring to a predetermined tension prior to locking the member against rotation in the spring-winding direction, the said mechanism consisting of a driving arm rotatable with and having a limited amount of movement relatively to the member and having engagement with the power spring whereby the driving arm is constantly urged in one direction of rotation, a control spring connecting the retrieving member and the driving arm and tending to rotate the driving arm in a direction opposed to that by the power spring but yielding to the tension of the power spring, means for varying the tension of the control spring and a spring actuated member carried by the driving arm and operat-

ing upon release of the latch to maintain the latch in a released position during rotation of the retrieving member by the power spring and for compelling the rewinding of 5 the power spring to a predetermined tension before the latch and retrieving member are interlocked.

24. The combination of a retrieving member, a casing wherein the member is rotatably mounted, a power spring for urging said member in one direction of rotation, means for rotating said retrieving member in the reverse direction and against the tension of said power spring, a lock movably secured to the casing and operable when in normal position to restrain the member against rotation in either direction, means operated by centrifugal force to release the lock, and mechanism connecting the spring 10 and the member, said mechanism comprising an element having engagement with said spring for transmitting power of the spring to the member and arranged for movement relatively to the member, and a yieldable 15 adjustable connection between the member and element normally yielding to the tension of the power spring.

25. The combination as set forth in claim 24, and means carried by said element and 30 actuated by the relative movement between said element and member for preventing engagement of the lock with the retrieving member prior to the rewinding of the power spring to a predetermined tension.

35 26. In a reeling device the combination of a case, a retrieving member mounted therein for rotation and provided with a slot, a spring constantly urging the retrieving member in one direction of rotation, means 40 for rotating the member in the other direction, a locking device movably supported by the case and adapted to enter said slot where it operates to lock the member against rotation, means for moving the locking device out of the slot to permit rotation of the member by the spring, means for preventing engagement of the locking device with the slot during rotation of the member by the 45 spring, and means dependent upon the tension of said spring for actuating the last mentioned means to permit engagement of the locking device with the slot when the spring is wound up to a predetermined tension.

55 27. In a reeling device the combination with a reel adapted to receive a rope, a casing wherein the reel is mounted, a spring normally held under tension for rotating the reel in a rope-winding direction and secured to the casing at one end, mechanism connecting the reel with the other end of the spring, a device for holding the spring under tension, and means for releasing the holding device and permitting the power of 60 the spring to be transmitted to the reel; of

means controlled by and dependent upon the winding up of the spring to a predetermined tension for limiting the winding up of the spring.

28. In a reeling device the combination of 70 a case, a reel rotatively mounted in the case, a spring connected at one end to the case and normally held under tension for rotating the reel in one direction and mechanism for normally holding the spring under tension, 75 of means connecting the other end of the spring with the reel and automatically adjustable relatively to the holding mechanism by the spring when wound from one tension to a greater predetermined tension 80 for controlling and locking the holding mechanism under tension.

29. In a reeling device the combination of 85 a case, a rotatable retrieving member mounted therein, a power spring for rotating the member in one direction, means for normally locking the member against rotation by the spring and thereby holding the spring under tension, a driving element between the spring and member having a connection with the spring and normally held in one position relatively to the member by tension of the spring for transmitting power of the spring to the member, and a second 90 spring connecting the member and element 95 for actuating the element relatively to the member when the tension of the power spring is relaxed, and means actuated by the relative movement between said element and member for preventing the locking means 100 moving into operative position prior to the winding up of the power spring to a predetermined tension.

30. The combination of a rotary retrieving member, a spring constantly urging the 105 member in one direction of rotation, means for rotating the member in the reverse direction and against the tension of the spring, and means controlled by the spring and operable after the spring has been wound up to 110 a predetermined tension for positively locking said retriever member against rotation in either direction.

31. An article of manufacture comprising 115 in combination a case, a retrieving member mounted therein, and provided with a slot, a spring tending to rotate the member in one direction, means for rotating the member in the other direction and against the tension of the spring, means secured to the case and 120 operable when set in said slot to lock the member against rotation in the direction urged by the spring, and means controlled by the tension in the spring for setting the locking means when the tension in the 125 spring has reached a predetermined amount.

32. An article of manufacture comprising 130 in combination a case, a retrieving disk therein, a spring tending to rotate the disk in one direction, means for rotating the disk

in the other direction and against the tension of the spring, means coacting with the case for locking the disk against rotation in the direction urged by the spring, means controlled and actuated relatively to the disk by the tension in the spring for setting the locking means when the tension in the spring has reached a predetermined amount and means whereby the tension required to operate the means controlled thereby is adjusted.

33. In a winding device of the character described, a retrieving member, a spring to rotate the retrieving member in one direction, means for locking the retrieving member against rotation by the spring and means controlled and continually acted upon by the tension of the spring for setting the locking means to prevent rotation of the retrieving member by the spring.

34. In a winding device of the character described, a rotatable retrieving member, a spring to rotate the member a plurality of revolutions in one direction, means to rotate the member in the other direction to wind up the spring, and means dependent upon the winding up of the spring to a predetermined tension for locking the retrieving member against rotation by the spring.

35. In a reeling device of the character described, two relatively rotatable members, a spring having one end secured to one of the members and constantly tending to rotate the other member in one direction, a second spring connecting the other end of the first mentioned spring to the other member, and means for adjusting said second spring.

36. In a trolley retriever, mechanism controlled and operated by the tension of the retrieving spring for controlling the setting of the device to normal operative position.

37. In a spring operated reeling device, mechanism controlled by the tension in the

spring to prevent winding the spring beyond the predetermined tension, such mechanism functioning regardless of the number of revolutions of any part of the reeling device.

38. A reeling device comprising a casing, a reel mounted therein and adapted to receive and wind up a rope, a power spring to rotate the reel, means whereby the spring is wound up by the rotation of the reel in a rope unwinding direction, means operating to check the winding of the spring beyond a predetermined tension in the spring, and means controlled by the tension in the spring and acting on the last named means to cause said means to function.

39. A reeling device comprising a casing, a power spring therein, a retrieving member rotatably controlled by the spring, means for locking the retrieving mechanism against rotation and holding the spring under a predetermined tension, means for winding up the spring, and means controlled by the tension in the spring to prevent winding the spring beyond the predetermined tension.

40. The combination of a rotatable retriever disk, a spring for rotating the disk in one direction, means for rotating the disk in the opposite direction and against the action of the spring, a locking device for locking the disk against rotation by the spring, means for co-acting with the locking device to hold the disk against rotation, and an element rotatable with the disk and having a limited amount of movement relatively thereto adapted to maintain the lock in released position while the spring is being wound up and dependent upon a predetermined tension of the spring for causing said locking device to move into locking position.

In testimony whereof I affix my signature.

SAMUEL S. MATTHES.
